SMOKE REGULATOR FOR PIPE STEMS,
CIGARETTE AND/OR CIGAR HOLDERS,
AND THE LIKE

James Henry Murphy, Shaker Heights, Ohio

Application December 13, 1934, Serial No. 757,321

1 Claim. (Cl. 131—12)

My invention relates, in its broadest aspect to a smoke regulator means for the bite end of pipes and the like, such means being adaptable to pipe stems, cigarette holder stems, cigar holder stems and the like for the purpose of protecting the tongue and the mucous membrane lining of the oral cavity of a smoker from irritation, and to prevent the smoke from entering into the mouth direct from the pipe stem or holder.

10 In the smoking of a pipe and the like, it is a well known fact that all pipe stems and the like at the bite end have a tendency to wear down the teeth of a smoker, and further, if the smoker has no teeth, then the bite end irritates the gums of the smoker.

15 Therefore the object of this invention is to provide a means whereby the smoke stream from a tobacco in a pipe bowl, or from a cigar or cigarette is baffled or diverted from a horizontal plane into a vertical plane, such diverting being accomplished by means of an expansion chamber in the smoke regulator.

20 It is also an object of the invention to make "smoking" more pleasant by causing the smoke to be diverted from one plane to another, such diverting thereof causing it to eliminate some of the nicotine contained therein.

25 It is also an object of the invention to provide a means on, in, or with a pipe stem smoke regulator which will cause the smoke to cool before entering the smoker's mouth.

30 It is also an object of the invention to provide an attachment for the bite end of a pipe stem and the like on the outside thereof which will save the wear on the incisal or occlusal edges or surfaces of the teeth used in holding a pipe or the like in the mouth.

35 It is also an object of the invention to provide a means, which when placed on, in, or with the bite end of a pipe stem and the like will increase the length of the smoke travel from the pipe bowl or the like to the mouth of the smoker.

40 It is also an object of the invention to provide a means which may be attached to, or placed on or in a pipe stem and the like and which will alter the plane of the smoke travel from one level to a higher level, and at the same time provide a volume enlarging chamber therebetween, wherein the smoke can expand, such expansion of the smoke causing it to cool slightly in accordance with the usual formulae governing the cooling of gases while expanding during work.

45 It is also an object of the invention to provide a means for the bite end of a pipe stem and the like, with an ingress therein, the purpose of which

5 is to permit moist air from the oral cavity or mouth of a smoker to enter into the expansion chamber, such tending to prevent a further rise of the pressure in the chamber, while at the same time serving as a regulator so that the mixture of smoke and moist air are simultaneously moved upward into the egress and thence into the mouth.

It is also an object of the invention to provide an efficient and compact smoke regulator for the 10 bite end of a pipe stem and the like having an interlocking means therein so as to enable it to be easily mounted on or in the pipe stem and interlocked therewith, such mounting being simple in construction, easily manufactured and easily re- 15 moved at any time for the purpose of inspection or cleaning.

It is also an object of the invention to provide a smoke regulator means in the bite end of a pipe stem and integral therewith, and when thus 20 made, then to insert or mount a covering means on the outside of the pipe stem for the purpose of protecting the teeth of a smoker from wear.

It is to be observed therefore in the present type of smoke regulators for use on pipe stems and the like, that their purpose is merely for sanitary purposes as well as to save the teeth, so that other than the results outlined the devices are generally considered unsatisfactory from the standpoint of 25 a smoker's comfort.

30 Therefore to overcome such defects, the type of smoke regulator used and which is the subject of this invention is constructed of rubber, or rubber compound, or elastic plastic compositions. It has considerable elasticity, and as well as being 35 made of the above compounds, it may also be made of any other suitable compound or compounds.

35 In the invention I find that elastic rubber is advantageous since it may be easily molded into the 40 desired shape and because of the convenience with which it may be applied and maintained in its desired position. It is made to fit on the outside with strict conformity to the shape of the pipe stem and/or the like, and may be mounted 45 detachably thereon, or it may be mounted in the end of the pipe stem, or it may be made integral with the pipe stem. A conventional shape as applied to a standard pipe stem is illustrated in Figure 1, and from which it will be observed that it 50 comprises top, side, bottom and an end wall which fits closely to the general contour of the stem end.

55 It must fit snugly upon or in the bite end of a pipe stem so as to exclude air and moisture from 55

entering in between the regulator and the pipe stem.

The means may be made in different sizes and shapes, and of different plastic materials having inherent elastic properties therein or otherwise. It may be of integral or composite structure, and may likewise be suitably colored.

Other objects will present themselves, from a perusal of this specification and claim, to those skilled in the art.

In the accompanying drawing, an illustrative example is shown of a construction of a pipe stem smoke regulator which will produce the desired objects outlined above, and which when placed on the outside or inside of the stem will at the same time through its interlocking means interlock itself securely in place on or in the bite end of the stem.

To better understand the invention—

Figure 1 is a vertical sectional view through the pipe and the smoke regulator.

Figure 2 is a horizontal sectional view of the regulator and a fragmentary view of the pipe stem.

Figure 3 is a horizontal plan view of the regulator and a fragmentary view of the pipe stem.

Figure 4 is a modified form in horizontal section showing the regulator integral with the stem, and also showing a means of plastic material in the pipe stem.

Figure 5 is a sectional side view of the stem shown in Figure 4 with the band removed therefrom.

Figure 6 is a side elevation of Figure 5, and showing a band inserted in the stem.

Figure 7 is a vertical section showing a modification of a method of attaching the regulator to a pipe stem.

Figure 8 is a horizontal section showing another modification of a method of attaching the regulator to a pipe stem.

Figure 9 is a vertical section of Figure 8 showing the expansion chamber formed in the end of a pipe stem and covered with a cap.

In the device illustrated in the drawing, the pipe is divided into a bowl portion 2 and a stem portion 3. Positioned at the bite end 4 of the stem portion on the outside thereof is a bead or flange 5. Throughout the stem portion is a passage or bore 6 which communicates with the bowl of the pipe as shown. The pipe may be of integral or composite structure. Positioned on or in the end portion of the stem portion and integral or otherwise with, is a smoke regulator means 7. It will be observed that the shape of the regulator is such as to encompass the stem snugly when used on the outside, and to fit snugly therein when positioned on the inside. On the regulator may be formed a bead means 8, the purpose of which is to strengthen the regulator at that point. The regulator has an internal recess 9 which cooperates with and snugly fits and interlocks with the bead 5 on the pipe stem. Provided in the regulator is a mixing or air chamber 10 from which is an egress or aperture 11, and a frusto conical or other suitably shaped ingress 12. The open end 13 of the regulator is restricted in such a manner as to form an air tight and moisture tight joint between the pipe stem and the regulator. The frusto conical or other suitably shaped ingress 12 in the regulator is an air inlet and is positioned below the egress 11. The egress may be of any suitable shape or size, or may be foraminous, and is positioned in the top side of the chamber of the

regulator and the end 15 of the pipe stem. The ingress opening 12 is very small when compared with the egress opening 11. Also on the regulator is positioned a bead means 16. When a regulator 20 is used to fit into the end of a pipe stem 19, the stem is equipped with an internal bead means 17 for the purpose of interlocking with the groove 18 in the regulator. When the regulator 22 is integral with a pipe stem 21, the pipe stem is provided with a band 23. The band 23 may be eliminated as shown in Figure 5 or it may be inserted therein as shown at 24 in Figure 6. The regulator may be constructed with an integral end wall 25 to provide a chamber 26, and the bite end of the stem is provided with a cap 27 having an internal bead 28 which interlocks in a groove 29 on the stem to hold the cap in place. The cap is provided with the usual egress and ingress openings.

It is to be understood that the specific terminology herein used is not intended to be restrictive or confining, since rearrangement of the parts and modifications of structural details may be resorted to in manufacturing the smoke regulator, and it is also to be understood that like references designate similar parts throughout the respective views.

In the investigation which led to this invention, the effect of embodying in the unit a mixing or air chamber located at the end of a pipe stem is to firstly, reduce the pressure of the smoke as it leaves the pipe stem; secondly, to allow the smoke to expand, such expansion causing the smoke to cool, and at the same time give forth some of the nicotine contained therein; thirdly, to permit moisture and air in the oral cavity to mix with the smoke before the smoke enters the mouth of a smoker; and fourthly, to increase the length of the smoke travel by changing the direction of the smoke from one plane to another.

The operation of the device is as follows. The unit is stretched over or inserted in the end of the pipe stem and fixed to place. The smoke is then drawn from the bowl to the mixing chamber, from which it later travels in an upward direction through an egress into the mouth of the smoker. When the smoke enters the mixing chamber or expansion chamber it is turned from its original direction at an angle of approximately 90 degrees therefrom. After leaving the mixing chamber it then travels upward through the egress into the oral cavity of the smoker, and instead of hitting or striking the tongue first, it strikes against the palate of the smoker.

As the smoke leaves the end of a pipe stem it is travelling at a high velocity into the mixing chamber. In the mixing chamber it expands and rotates centripetally therein, such expansion and rotating causing the moisture and air in the mouth to enter through the small ingress into the mixing chamber where it becomes mixed with the smoke. Such mixing causes the temperature of the smoke to drop, so that on leaving the mixing chamber it travels through the large egress to strike the palate instead of the tongue. As the smoke leaves the egress it again expands into a large cavity or oral cavity, which expansion reduces the temperature and pressure, thus rendering the smoke non-irritating to the mucous membrane lining the oral cavity, and thus eliminates a very undesirable feature of smoking.

As the smoke expands and centripetally rotates

in the mixing chamber, much of the nicotine contained therein is thrown therefrom, and leaves the mixing chamber by bleeding from the small ingress in the bottom side of the device.

5 As the smoke travels from the mixing chamber into the mouth, it is constricted as it flows through the large egress. This constricting or squeezing of the moisture laden smoke through the egress causes moist air from the oral cavity to be sucked 10 or drawn through the ingress and then into the hot or warm smoke where it thoroughly mixes.

Any saliva or nicotine which might find its way into the mixing chamber may drain through the ingress in the bottom of the device into the mouth 15 of the smoker, from which it may be eliminated. In this manner the device tends to prevent the saliva and nicotine from being forced back into the pipe stem as is now found in the ordinary smoking pipe.

20 Again as the smoke expands in the mixing chamber, and as it passes through the egress it has a tendency to force the saliva away from the egress thus preventing its entry into the chamber from that point. The expansion of the smoke in the chamber will also prevent the saliva from entering into the small ingress. In order that this invention will function according as herein written it is to be understood that the ingress is 25 extremely small in cross section when compared

with the egress in cross section. By having the egress very large in cross section compared with the ingress cross section, the smoke as it passes through the stem into the expansion chamber of the unit will on its expansion draw or suck moisture from a smoker's mouth into the chamber, and while this process is going on the moisture laden smoke flows from the large egress into the mouth of a smoker. 5

While I have herein shown and described a preferred arrangement, it will be readily understood that changes and modifications therein may be found desirable or essential in meeting the various exigencies of use, and I desire to be understood as reserving the right to make any and all such 10 changes or modifications as may be found desirable or essential in so far as the same may fall within the spirit and scope of the invention as expressed in the accompanying claim when broadly construed. 20

What I claim is:

In a smoke regulator for pipes and the like, comprising, a chambered portion; a chamber therein; a smoke egress in the upper portion of the chambered portion; an air ingress in the lower portion 25 of the chambered portion, and substantially below the smoke egress; and a stem attaching portion integral with the chambered portion.

JAMES HENRY MURPHY.
